GERMANY.

REVOLVING RING-HEARTH OVEN.

Application filed June 2, 1926, Serial No. 113,284, and in Germany June 2, 1925.

This invention relates to a revolving ring hearth oven in which the material for the purpose of being dried, subjected to dry distillation, degasification or other treatment, is spread in the form of a thin layer on a revolving ring hearth in order to be exposed to the effect of heat during continuous working. More particularly the invention is concerned with revolving ring hearth ovens of the type in which the revolving hearth is carried on annularly arranged supports and is rotated by driving means arranged on the said supports outside of the oven. In such ovens a considerable difficulty arises in connection with the heat insulation of the heated oven chamber against the outer chambers, which insulation is necessary in order on the one hand to confine the oven heat, and on the other to protect the supporting and driving means from the effect of the considerable heat of the oven.

Per se it is known for the purpose of insulation in revolving ring hearth ovens to provide sand troughs into which dip ribs vertically arranged on the edge of the hearth.

The object of the invention is an arrangement whereby on the one hand the heat insulation of the oven chamber against the outside is improved, and on the other hand the maintenance of the supporting and driving means in a cool condition is facilitated.

To this end in revolving ring hearth ovens having a gas closure, provision is made according to this invention between the oven chamber and the supporting and driving means of the hearth and beyond the gas closures such as sand troughs arranged in proximity to the edge of the hearth, of annular water cooled troughs into which dip annular cooling ribs on the revolving hearth or supporting means.

Particular difficulties are encountered when such revolving hearths are to be heated from below which in itself is of material advantage since the heating agent usually of a gaseous nature need in that case not be conveyed to the oven chamber proper, and a mixture with the products frequently containing valuable and recoverable constituents is thereby avoided, while the direct contact heating is nevertheless maintained.

In order to overcome these difficulties a revolving ring hearth oven according to this

invention is constructed with an arrangement for heating from below so that between two concentrical heating flues properly packed by sand troughs on the hearth edges against the oven chamber a space is created which, insulated against the heating flues by sand troughs or the like, accommodates the upper portion of the supporting means, such as a supporting ring, and is insulated from the space containing the driving means by means of cooling water troughs and ribs of the supporting ring dipping therein. By this arrangement an advantageous heating of the ring hearth from below is rendered possible in spite of the fact that the supporting and driving means are completely protected against the influence of the heating.

Moreover by the particular arrangement the isolation of the heating chamber in regard to the outflow of heating gases is considerably improved.

A constructional form of the invention is illustrated by way of example in the annexed drawing in more or less diagrammatical views.

Fig. 1 is a fragmentary sectional view of the improved oven taken substantially on the line 1-1 of Fig. 2, and

Fig. 2 is a plan view from above on a reduced scale.

The oven as shown is provided with an annular chamber *a* covered by the oven arching which may comprise an inner brick arch *b* and an upper flue *c* which is covered by insulating brick-work *d* with an interposed insulating layer *e*. Built into the lower portion of the oven are two annular heating flues *f*, *f'* which are traversed by heating gases in the direction of the arrows *g*, *g'* admitted respectively by way of the inlet sockets *A* and *B*. The heating flues *f*, *f'* extend from the inlets *A*, *B* concentrically around and below the whole oven chamber to the outlet sockets *A'*, *B'* through which latter the heating gases are led off (see Fig. 2). The heating flues are open towards the oven chamber and are bridged by the ring hearth *h* which consists of heat conducting substances, such as metal. The ring hearth is provided with downwardly depending annular ribs *i'* which dip, respectively into sand troughs *k*, and *k'* arranged in the walls of the heating flues. The sand troughs *k* close the heating flues against the oven

chamber, while the sand troughs k' are provided to close the same against a central space or annular channel l located between them. Accommodated in this space or channel is the upper part of the carrier ring m . This space is closed at the bottom by two troughs n, n' which are charged with cooling water and into which dip annular ribs o depending from the carrier member m of the hearth. In this way the space l is closed against the space located below the oven, and heat transmission through the carrier member m to the driving device p which is located below the oven, is completely avoided.

We claim:—

1. In a revolving ring hearth oven, a body having an annular oven chamber and spaced concentric heating flues communicating therewith, a space between said flues forming an annular channel, a revolving ring hearth supported in said chamber above said flues, a supporting member for the hearth depending therefrom into and through said channel, driving means for rotating said supporting member located below said chan-

nel, troughs at the lower end of said channel for containing a cooling medium, said supporting member having portions projecting into said troughs to reduce the transmission of heat from said hearth to said driving means, inner and outer troughs extending about the upper ends of said heating flues beneath said hearth, and ribs formed on said hearth and depending into said inner and outer troughs.

2. In a revolving ring hearth oven, a body having an annular oven chamber and spaced concentric heating flues communicating therewith, a revolving ring hearth supported in said chamber above said flues, a supporting member for the hearth depending therefrom between said flues, driving means for rotating said supporting member, inner and outer troughs extending about the upper ends of said heating flues beneath said hearth, and ribs formed on said hearth and depending into said inner and outer troughs.

In testimony whereof we have signed our names to this specification.

LUDWIG HONIGMANN.
FRIEDRICH BARTLING.
